CYRUS J. FAY, OF PHILADELPHIA, PENNSYLVANIA.

Letters Patent No. 65,895, dated June 18, 1867.

IMPROVED BELTING.

The Schedule referred to in these Letters Patent and making part of the same.

TO ALL WHOM IT MAY CONCERN:

Be it known that I, C. J. FAY, of Philadelphia, in the county of Philadelphia, and State of Pennsylvania, have invented a new and useful Improvement in Belting; and I do hereby declare that the following is a full, clear, and exact description thereof, which will enable others skilled in the art to make and use the same, reference being had to the accompanying drawings, forming part of this specification, in which—

Figure 1 represents a longitudinal sectional view of my improved belt.

Figures 2 and 3 are face views of the same.

Similar letters of reference indicate like parts.

This invention relates to the use of paper made of manilla, hemp, or grass, according to the process and mode described in the specification accompanying the Letters Patent granted to T. Irving, J. McNeil, George W. Rich, and Cyrus J. Fay, on the 18th day of December, 1866, for the purpose of belting of any description for machinery, &c., and also for harnesses and other similar purposes.

The extraordinary strength and durability of this paper, its water-proof and elastic qualities, and its great cheapness, make it peculiarly adaptable for the purposes above referred to. The paper to be used for belts can be made in strips of the requisite width, and of any desirable length. Any number of layers of paper are pasted or otherwise secured together to get the requisite thickness and strength. I have found that rubber cement will be the best agent for pasting the different layers of paper together, as it is impervious to moisture, and as it adds to the pliability of the belt. The layers of paper may be sewed together as indicated in fig. 2, and I consider that the best and most complete process for the purpose. The ends of such a belt may be laced together in the usual manner.

The great strength of this paper permits the use of comparatively thin belts, where heretofore the thickest kinds of leather belts were used. The paper belt will not stretch or expand, and is impervious to water, will therefore not be softened and lengthened when moistened, as the leather belts do. A paper belt of the above construction will cost but one-fourth of what would be the price of a leather belt having the same strength.

The invention may also be used with advantage for certain parts of harness, and in fact wherever leather straps are now used. Such harness straps could be coated with any suitable paint, and be enamelled or otherwise ornamented in any suitable manner.

I claim as new, and desire to secure by Letters Patent—

The use of and the manner of arranging paper for belts and straps, substantially as described.

The above specification of my invention signed by me this 23d day of February, 1867.

C. J. FAY.
